UNITED STATES PATENT OFFICE.

CHARLES TRECOTT RIPLEY, OF CHICAGO, ILLINOIS.

PACKING MATERIAL FOR JOURNAL-BOXES AND THE LIKE.

1,298,794.

Specification of Letters Patent. Patented Apr. 1, 1919.

Application filed July 22, 1918. Serial No. 246,218.

To all whom it may concern:

Be it known that I, CHARLES T. RIPLEY, a citizen of the United States, residing at Chicago, in the county of Cook and State of Illinois, have invented certain new and useful Improvements in Packing Material for Journal-Boxes and the like, of which the following is a specification.

My invention relates to a product usable as a packing material for journal boxes, though probably susceptible of being used in other analogous situations.

The primary object of the invention is to provide an improved and inexpensive packing material for journal boxes or the like which have greater capillary and resilient qualities than the various forms of packing material now used, and which may be applied and used in accordance with the present customs which have been established in connection with the use of woolen and cotton waste.

The packing material of my invention consists of a body of absorbent or capillary material such as woolen or cotton waste (cotton being preferred for economy), having a plurality of coiled springs embedded in the said waste to give it the necessary resiliency to hold it up against the under side of the journal. The coiled springs may be embedded in the waste in any suitable manner though they are preferably inserted by means of a screwing action which causes the coils of the springs to be interwoven with the waste.

The use of cotton waste alone as a packing material for journal boxes has not proved satisfactory in practice, because of the lack of resiliency of the waste when it is impregnated with oil. The use of woolen waste is preferable in this connection but this material is expensive and it has likewise failed to be entirely satisfactory, as its resiliency is insufficient to hold it up against the journal at all times, thereby requiring considerable attention to keep it in proper working condition. Several attempts have been made to overcome these disadvantages, such, for example, as the provision of the journal boxes with spring bottoms adapted to hold the material up against the under side

of the journal. Such expedients, however, have proven impractical as they have a tendency to compress the waste in a manner to interfere with the capillary action and cause the packing to heat very quickly. These devices are also very difficult to maintain. By the use of a plurality of coiled springs embedded in the waste, the entire body of material is maintained in loose and open yet resilient condition, the wire coils serving as a resilient frame which prevents the interior of the waste from being over compressed while keeping the waste up against the journal.

A more thorough understanding of my invention may be had by referring to the accompanying drawing in which I have shown a packing material, made in accordance with my invention, applied to a journal box of a railway car.

Figure 1 is a longitudinal section through a journal box showing the packing material in position, and

Fig. 2 is a cross section taken on line 2—2 of Fig. 1.

Referring to the drawing, 10 is one of the journals of a railway car, 11 the journal box and 12, 13 the journal brass and wedge, respectively, interposed between the journal and the top of the journal box. A twisted strip 14 of the packing material is preferably arranged, in accordance with the established custom, adjacent the space 15 intervening between the under side of the journal and the journal box. This arrangement prevents dirt from entering the box through said space and also prevents any loose portions of the main body 16 of the packing from working through the space 15. The coiled springs, designated in the drawing at 17, are preferably large enough in diameter to prevent them from being accidentally forced into the space 15 when the journal box is being packed.

As shown by the drawing, in order to provide sufficient resiliency in all directions of the packing material the springs, made preferably of fine wire in the form of open coils, that is, with the turns considerably spread apart one from the other, are preferably screwed into the body of woolen or

cotton waste, as the case may be, in various directions without any fixed relation to each other.

I claim:

- 5 1. A packing material for journal boxes, or the like, comprising a mass of absorbent material having a plurality of open coiled springs interwoven therein.
2. A packing material for journal boxes,

or the like, comprising a mass of cotton 10 waste having coiled wire springs interwoven therewith.

3. A packing material for journal boxes, or the like, comprising a mass of thread-like material having capacity for absorbing 15 a lubricant, and a plurality of coiled springs interwoven with said material.

CHARLES TRESCOTT RIPLEY.
